200,595

DRAWING STENCIL

Heinz Adolf Herman Wendt and Allan Arthur Ebzery,
both of 28 Wellington St., St. Kilda, Victoria, Australia

Filed Jan. 31, 1964, Ser. No. 78,447

Claims priority, application Australia Aug. 7, 1963

Term of patent 14 years

(Cl. D52—6)

FIG. 1 is a top plan view of a drawing stencil, showing our new design;

FIG. 2 is a bottom plan view thereof;

FIG. 3 is a side elevational view thereof; and

FIG. 4 is an end elevation of the stencil.

We claim:

The ornamental design for a drawing stencil, as shown.

References Cited by the Examiner

UNITED STATES PATENTS

D. 133,097 7/42 Carr ----- 52—6
D. 148,434 1/47 Owen ----- 52—6

OTHER REFERENCES

C-Thru Ruler Co. catalog, October 1957, protractor ruler at top of left column on page 2.

WALLACE R. BURKE, Acting Primary Examiner.